United States Patent Office

Des. 215,508
Patented Sept. 30, 1969

215,508

COMBINED TRAFFIC SIGNAL AND SUPPORT BRACKET THEREFOR

Leonard N. Albrecht, Mill Valley, Calif., assignor to
Tamar Electronics Industries, Inc., Los Angeles, Calif.,
a corporation of Delaware

Filed Dec. 18, 1968, Ser. No. 15,042

Term of patent 14 years

Int. Cl. D29—99

U.S. Cl. D72—1

FIG. 1

FIG. 2

FIG. 3

FIG. 1 is a perspective view of the combined traffic signal and support bracket therefor, showing my new design,

FIG. 2 is a side elevation view of the combined traffic signal and support bracket therefor,

FIG. 3 is a top plan view of the combined traffic signal and support bracket therefor,

FIG. 4 is a front elevation view of the combined traffic signal and support bracket therefor,

FIG. 5 is a side elevation view of the combined traffic signal and support bracket therefor from the side opposite to that shown in FIG. 2,

FIG. 6 is a back elevation view of the combined traffic signal and support bracket therefor, and

FIG. 7 is a bottom plan view of the combined traffic signal and support bracket therefor.

The fragmentary broken line showing of a post in FIGS. 2, 4, 5 and 6 is for illustrative purposes only.

I claim:

The ornamental design for a combined traffic signal and support bracket therefor, as shown and described.
